UNITED STATES PATENT OFFICE.

MARTIN J. PALMER AND WILLIAM H. BURTON, OF BEARDSTOWN, ILLINOIS.

CARPET-BEATER.

1,112,314.

Specification of Letters Patent. Patented Sept. 29, 1914.

Application filed October 16, 1913. Serial No. 795,525.

To all whom it may concern:

Be it known that we, MARTIN J. PALMER and WILLIAM H. BURTON, citizens of the United States, residing at Beardstown, in the county of Cass and State of Illinois, have invented new and useful Improvements in Carpet-Beaters, of which the following is a specification.

This invention relates to improvements in carpet beaters, and it proposes a portable machine constructed to efficiently liberate the dust from carpets or rugs as they lie in place upon the floor.

The object of the invention is to provide a compact and inexpensively constructed machine capable of ready operation by manual power, readily movable along the carpet or rug to be cleaned, and having instrumentalities for rapidly and thoroughly liberating dust from the fibers of the carpet or rug.

Further objects of the invention are to provide a machine having the advantages stated, constructed to uniformly clean a relatively large area of the carpet or rug in any given position thereon; having an organization of strong and durable nature; and embracing parts which are not liable to derangement and which are readily accessible for the purpose of renewal or repairs.

An embodiment of the invention is illustrated in the accompanying drawings, wherein:

Figure 1 is a front elevation of a machine in which the features of the invention are incorporated; Fig. 2 is a side elevation thereof; Fig. 3 is a horizontal sectional view on the line 3—3 of Fig. 2, the beaters and their appurtenances being shown in plan.

Similar characters of reference designate corresponding parts throughout the several views.

The instrumentalities of the machine are supported by a frame which includes a pair of vertical bars 1 and a base bar 2 connected to the lower ends of the bars 1 and projecting for substantial and equal distances beyond said bars 1. The bars 1 are disposed in upright relation and their upper portions are curved inwardly until they meet, and are then extended in parallel relation to afford a hand grip 3.

In the embodiment disclosed, the carpet beating instrumentalities are arranged in duplicate, and in each instance comprise a rocker bar 4 arranged in advance of the base bar 2 and connected to the upper face of the

latter by spring hinges 5 and a beater 6 carried by said rocker bar. The beaters 6 are preferably constructed of wire, and consist in each instance of a pair of members having interengaging coils 7 and having arms 8 which project in diverging relation beyond the coils 7. The inner terminals of the wire members which compose each beater 6 project under a rocker bar 4 and are connected to said rocker bar, preferably by having angularly extending portions 9 which are secured in openings or recesses extending from the under face of said rocker bar. The construction of the beaters disclosed in the drawings, while preferred, is not obligatory.

The rocker bars 4 are arranged symmetrically with relation to the vertical center of the base bar 2 and the operating means employed is common to said rocker bars and consists essentially of a wheel 10 arranged mid-way between the bars 1 and mounted on an axle 11 which is carried by said bars. The wheel 10 is provided at each side thereof with laterally projecting studs 12 for engagement with angularly disposed arms 13 which are carried by the bars 4. Where the beating instrumentalities are arranged in duplicate, as in the embodiment shown, it is preferred that the beaters all work in alternation, and for this purpose the studs 12, at one side of the wheel 10, are arranged in staggered relation to the studs 12 at the opposite side of said wheel. Any convenient means may be employed for rotating the wheel 10. By preference, the wheel 10 is formed with sprocket teeth and is driven by a chain 14 from a sprocket wheel 15 which is arranged centrally between the bars 1 and is mounted on a shaft 16 journaled in said bars and having at one end thereof a crank handle 17. The shaft 16 is arranged at such an elevation on the bars 1 that its crank handle 17 is within easy reach of the operator.

The operation will be readily apparent from the foregoing description. The machine is placed at any desired location on the carpet, and the crank handle 17 is rotated to effect a clockwise movement of the wheel 10. During the rotation of the wheel 10 its studs 12 successively engage the arms 13 of the rocker bars 4, and by virtue of such engagement, move said rocker bars on their hinges 5 and lift the beaters from the carpet. When the studs 12 disengage the arms 13, the springs of the hinges 5 move the

rocker bars downwardly and cause the beaters to strike the carpet with considerable impact. The number of strokes of the beaters depends upon the number of studs 12, and the rapidity of the rotation of the wheel 10. The force with which the beaters engage the carpet can be increased by tilting the bars 1 forwardly so as to cant the bar 2 relatively to the rocker bars 4, and to increase the tension of the springs of the hinge joints 5. The carpet beater herein described will clean a relatively large area in any given location, and will do its work quickly and thoroughly, and when a particular area of the carpet has thus been cleaned, the beater may be easily moved into position to clean some other portion of the carpet.

The construction is inexpensive to manufacture, strong, accessible, and light in weight.

Having fully described our invention, we claim:

1. In a portable carpet beater, a base bar adapted to rest directly upon the carpet *in situ*, a rocker bar parallel to the base bar, spring hinge connections between the base bar and the rocker bar, a beater carried by the rocker bar, an upright frame of which the base bar forms a part and which has a handle at its upper end, and manually operated means carried by said upright frame for periodically moving said rocker bar about its hinge connections as an axis.

2. In a portable carpet beater, a base bar adapted to rest directly upon the carpet *in situ*, a rocker bar parallel to the base bar, hinge connections between the base bar and the rocker bar, a beater carried by the rocker bar, an upright frame of which the base bar forms a part and which has a handle at its upper end, and manually operated means carried by said upright frame for periodically moving said rocker bar about its hinge connections as an axis.

3. In a portable carpet beater, a base bar adapted to rest directly upon the carpet *in situ*, a rocker bar parallel to the base bar, spring hinge connections between the base

bar and the rocker bar, a beater carried by the rocker bar, an upright frame of which the base bar forms a part and which has a handle at its upper end, and manually operated means carried by said upright frame for periodically moving said rocker bar about its hinge connections as an axis, the means including a wheel provided with laterally projecting studs and an angularly disposed arm carried by the rocker bar for engagement by said studs.

4. In a portable carpet beater, a base bar adapted to rest directly upon the carpet *in situ*, a pair of juxtaposed rocker bars parallel to the base bar, hinge connections between the rocker bars and the base bar, beaters carried by the rocker bars, an upright frame of which the base bar forms a part and which has a handle at its upper end, and manually operated means carried by the frame and common to said rocker bars for periodically and alternately moving them about their hinge connections as axes.

5. In a portable carpet beater, a base bar adapted to rest directly upon the carpet *in situ*, a pair of juxtaposed rocker bars parallel to the base bar, spring hinge connections between the rocker bars and the base bar, beaters carried by the rocker bars, an upright frame of which the base bar forms a part and which has a handle at its upper end, and manually operated means carried by the frame and common to said rocker bars for periodically and alternately moving them about their hinge connections as axes, the means including a wheel having laterally projecting studs at each side thereof and angularly disposed arms carried by the rocker bar for engagement by said studs.

In testimony whereof we have hereunto set our hands in presence of two subscribing witnesses.

MARTIN J. PALMER.
WILLIAM H. BURTON.
